F. GOEBEL.

PARLOR STOVE.

No. 17,212.

Patented Mar. 29, 1887.

UNITED STATES PATENT OFFICE.

FRITZ GOEBEL, OF TROY, NEW YORK, ASSIGNOR TO THE CO-OPERATIVE STOVE WORKS, OF SAME PLACE.

DESIGN FOR A PARLOR-STOVE.

SPECIFICATION forming part of Design No. 17,212, dated March 29, 1887.

Application filed February 8, 1887. Serial No. 220,987. Term of patent 7 years.

To all whom it may concern:

Be it known that I, FRITZ GOEBEL, of the city of Troy, county of Rensselaer, State of New York, have invented and produced a new 5 and ornamental Design for Parlor-Stoves, of which the following is a specification.

My design relates to the form and ornamentation of parlor-stoves, as the same is shown in the accompanying photograph, forming a 10 part of this specification, in which the several parts of the stove are designated by letters and the ornamentation by numbers, and as follows:

The letter T designates the top zone of the 15 stove, which is transversely cylindrical in form and smaller in its transverse diameter than the body part of the stove below it, and is composed of the dome D, ornamented with the recessed panels 1, having the interiorly-displayed 20 sprigs 2, the fretted dome-base molding 3, the fretted overhanging ovolو molding 4, and the cylindrical-form member 5, the latter being ornamented exteriorly by panels 6, which at the front contain the centrally-arranged 25 medallion figure 7 and at the sides the centrally-placed rosette figure 8, with said panels containing also, arranged around said centrally-placed figures, the scroll-work 9 and relief figures 10.

The letter B designates the body part, which 30 has a convexly-rounded front and sides, with pilastered corners arranged at right angles to each other; and this body is made to laterally subtend the upper zone, T, and to be 35 smaller in its lateral measurement than the ash-pit section A, that is below it. This body part is formed with a platform-top, 11, where subtending laterally the top zone, and this platform-top has its front and side edges 40 rounded outwardly between the corners, which latter are projectingly rounded out, as at 12. The platform-top has a flat molding, 13, arranged thereon for the display of the trade-name of the stove, and each of the corners of 45 the platform-top has an upwardly-projected urn-form ornament, 14.

The letter P designates corner pilasters, which at the top are ornamented with a hooded gargoyle figure, 15, a leaf ornament, 16, below 50 the latter, a column-cap, 17, and a leaf ornament, 18, extending to the bottom of the pi-

laster. The body part, below the overhang of the platform-top and where above the doors, has an ornamentation of scroll and vine form figures, 19.

The frames of the upper doors, D², of the body part are exteriorly milled, as indicated at 20, and the vertical sash-styles have a chain ornamentation, 21, terminating in a cap, 22, at the top. The corners of the doors are interiorly rounded, and the horizontal sash-bar 23 of the door-frames has arranged thereon the branching scrolls 24, with side bracket ornaments, 25, and a central ornament, 26.

The bottom doors, D³, have their frame exteriorly milled, as indicated at 27, and their vertical stiles made with a cap and chain ornamentation, like the upper doors, D². The horizontal sash-bar of the lower doors (indicated at 29) is arranged in the frame so as to 65 make the upper panes smaller than the lower, and their sash-bar is ornamented with a branching scroll, 30. The body between the upper and lower doors has a projecting band-molding, 37.

The ash-pit section A is rectilinear in form, having an overhanging platform-top, 38, that has rounded corners and the upper surface of which curves downwardly and outwardly, so as to overhang the walls of the ash-pit section, 80 this top having upon its upper surface the scalloped ornamentation 28 and the filleted edge 39. The corners of the ash-pit section have pilasters 34, that curve inwardly and upwardly from their plinths 35 (which are molded 85 and mitered) up to their foliated caps 36. The foot-rails R R each have a double bracket, 37, composed of the reversing convolute scrolls 38 and 39, and one of these foot-rails is arranged at each side of the ash-pit section. The 90 front of the ash-pit section is ornamented with a foot-rest, 58, which is attached to and projected from the front of the ash-pit door, and is therefrom extended downwardly, and has feet 40, which rest upon the base.

The base N is rectilinear in its transverse form, having rounded corners 41, and it is composed of the ogee molding 42, having scallops 43, dots 44, fret 45, and bottom fillets, 46 and 47. This base has a curtain, 48, arranged 95 between the feet F. The lower and pendent edge of this curtain is scalloped, notched, and

filleted, and the curtain exterior face, where between the fillets, is ornamented with a centrally-arranged medallion figure, 50, and at the corners by a wreathed medallion figure, 51, and the scroll-work in relief, 52. The lower edge of this curtain is notched, scalloped, and filleted.

The feet F have in their front vertical face an incuse ornamented with three birds' talons, 53, arranged in relief between a bordering fillet, with the body of the feet at their inner face curving in form to correspond with that of their front face. The sides of the feet 54, where extended downwardly from the stove-base, join the foot-rest in oppositely-reversing ogee curves, and the foot-rest of each foot has its front vertical face rounded at 55.

Having thus described my design, what I claim, and desire to secure by Letters Patent, 20 is—

1. The design for the form of a stove, consisting of the cylindrical upper zone, T, having a transverse diameter that is smaller than that of the body part below it, a body part, B, 25 having four pilastered corners and its exterior surface whereon the doors are placed between the pilasters rounded outwardly, a rectangular ash-pit section, A, having rounded corners, said ash-pit section laterally subtending the 30 body part, and a rectilinear curtained base, N, having rounded corners, as shown and described.

2. In a design for a stove, the top zone, T, consisting of the dome D, ornamented with the recessed panels 1 and displayed sprigs 2, the fretted dome-base molding 3, the fretted overhanging ovolo molding 4, and the cylindrical-form member 5, ornamented with the panels 6, having the medallion 7 on the front, the

rosette figure 8 on the side, and the scroll-work 40 9 and the relief figures 10, as shown and described.

3. In a design for a stove, the body part B, consisting of the corner pilasters, P, platform-top 11, and outcurves 12 between each of the 45 pilasters, the projecting band-molding 37, and doors D² and D³, corresponding in outcurve to that of the body, as shown and described.

4. In a design for a stove, the upper doors, D², consisting of the exteriorly-milled frames 50 20, having rounded interior corners, vertical sash-stiles having a chain ornamentation, 21, and cap 22, and branching scrolls 24, having side bracket ornaments, 25, arranged on the horizontal sash-bar, as shown and described. 55

5. In a design for a stove, the ash-pit section A, consisting of the overhanging scalloped and filleted top 38, having rectilinear sides and rounded corners, the corner pilasters, 34, the side brackets, 37, having scrolls 60 38 39 and foot-rails thereon, and the foot-rest 58, having ornamental feet 40, as shown and described.

6. In a design for a stove, the feet F, of the shape and ornamentation shown, consisting of 65 three bird-talons arranged in relief on an extended and bordering fillet, and base of the feet having a plain border with vertical sides departing in reversing ogee curves, as shown and described. 70

Signed at Troy, New York, this 20th day of July, 1886, in the presence of the two witnesses whose names are hereto written.

FRITZ GOEBEL.
